UNITED STATES PATENT OFFICE

ANDREW GRAHAM SHIELDS, OF ATTLEBORO, MASSACHUSETTS, ASSIGNOR TO FILL-KWIK COMPANY, OF ATTLEBORO, MASSACHUSETTS, A CORPORATION OF MASSACHUSETTS

CONTAINER

Application filed March 30, 1932. Serial No. 601,909.

My invention relates to containers and refers particularly to containers adapted for use with cosmetics and other adaptable commodities.

Many devices have been invented to contain a plurality of cosmetics in a compact and convenient manner, and the greater number of these are so constructed as to carry removable and replaceable cosmetics.

In order to replace exhausted cosmetics in containers of this character, the device is so constructed that trays carrying cosmetics, such as powder compacts, lip paste, rouge and similar products, may be inserted therein and withdrawn when the contents of the trays have been used.

These cosmetics trays, or so-called "refills", consist of a bottom member and upwardly extended sides, within which the cosmetic is positioned and so attached as to prevent its accidental displacement.

The usual method of removably fixing these cosmetics trays within the container is to place them in the container element adapted for their reception and retaining them therein by means of projections extending from the sides of the container into depressions in the sides of the trays, or by frictional contact only.

All of these methods for the removable retention of the trays within the container possess many disadvantages, among which may be mentioned, the accidental springing of the sides of the container will remove the projections from the recesses, releasing the tray; when the container is opened for use, the pressure of the holding hand will release the retaining means; the agitation of the container within the hand bag of the user is liable to jar the retaining means from holding contact; the friction of the powder puff, or finger, over the cosmetic for purposes of use is liable to dislodge the tray; the exposed sharp edges of the trays are liable to injure the powder puff or the fingers of the user; the appearance of the cosmetic-carrying portion of the container is uncouth, unfinished and inartistic as it presents a plurality of trays with their sharp edges exposed.

My device overcomes all of the above men-

tioned, and other, objectionable features of the present employed removable cosmetic containers as will be evident upon a consideration of this specification and its accompanying drawing.

In the accompanying drawing illustrating modified forms of the device of my invention, similar parts are designated by similar numerals.

Figure 1 is a plan view of one form of my device in open position, partly broken away for clearness of description.

Figure 2 is a reversed bottom view of the device of Figure 1.

Figure 3 is an enlarged section through the line 3—3 of Figure 1.

Figure 4 is an enlarged section through the line 4—4 of Figure 1.

Figure 5 is a perspective view of the trays and container in unassembled positions.

Figure 6 is a fragmentary vertical section of a modified form of my device.

The particular form of the device of my invention shown in the accompanying Figures 1 to 5 inclusive consists of a bottom member and a top member capable of placement in abutment to form an enclosing casing particularly suitable for containing a plurality of toilet preparations.

The bottom member consists of a bottom 80 10, the sides 11 and 12 and the ends 13 and 14. A platform, or frame 15 extends across the bottom member intermediate of its bottom 10 and the upper edges of its sides and ends and has two rectangular openings 16 and 17 85 therein. The peripheral edges of the frame 15 around the longer sides of the openings 16 and 17 are inclined downwardly as 18, 19 and 20. The members 22, 22 of the end 13 of the bottom member and the end portion 23 90 of the frame 15 are hinged to the pintle 24. The plate 31 attached to the member 32 of the frame 15 has an extended member 33 placeable below the extension 25 of the bottom end 14 to retain it in closed position. The frame 95 15 can thus be moved around the pintle 24 into the position 15' shown in dot-and-dash in Figure 3 and completely over as shown in Figure 2.

A cover 26 for the opening 16 is carried by 100

the pindle 27 and has the thumb piece 28. A downwardly extended tongue 29 is capable of placement through an opening 30 in the frame 15 and extends thereunder to retain 5 the cover 26 in closed position.

A tray 34 having the inclined sides 35 and 36 is slideable above the members 18 and 19 of the frame 15; and a tray 37 having the inclined sides 38 and 39 is slideable above the 10 members 20 and 21 of the frame 15. The sides 35 and 36 as well as the end extensions of the tray 34 are beneath the frame 15 and extend beyond the opening 17, and the sides 38 and 39, as well as the end extensions of the 15 tray 37 are beneath the frame 15 and extend beyond the opening 16.

To load the device, the frame is raised to the position 15' of Figure 3, a tray 34 carrying a suitable cosmetic 40 is slid into position 20 as shown in Figure 3, and a tray 37 carrying a suitable cosmetic 41 is slid into position as shown in Figure 3, and the frame 15 moved into the position shown particularly in Figures 1, 2 and 3. When the device is in this 25 position, the trays 34 and 37 cannot move either longitudinally or transversely of the bottom member. A powder puff 42 may be placed over the cosmetic 40.

It will be noted that all of the edges of the 30 cosmetic trays are covered by frame 15, thus giving the device the appearance of framed cosmetics.

A cover, or top, consists of a top 43, sides 35 44 and 45 and ends 46 and 47. The extended members 48, 48 of the cover top 43 is hinged to the pindle 24. A catch 49 co-operates with the hook 50 to maintain the cover in closed 40 position. A mirror 51 is carried by the inner face of the cover top 42.

In the modification shown in Figure 6, the frame 15 is not hinged to the pindle, but is retained in position by the edge of the plate 15 being positioned beneath the hinge of pindle 24. The other elements of the device 45 of Figure 6 are similar to those previously described.

While I have shown the cover, or lid, as 50 operating simply as a covering means for that portion of my device carrying the cosmetics, it is evident that it may also be of such construction as to carry cosmetics, thus forming a duplex container.

I do not limit myself to a single opening in the frame member as mentioned specifically 55 in my claims and the claims are intended to, and do, include a plurality of such openings.

It will be noted that the cosmetic trays are 60 enclosed between the bottom portion of the device and the tray carrying frame 15 in such a way that they are not affected by any spring, or distortion, of the bottom sides; that they are retained from dislodgment when the cover is in open position for use; that they cannot be dislodged by contact movement of 65 a puff or fingers; that the puff, or finger, is

protected from contact with the sharp edges of the trays and that the appearance is greatly improved by covering the edges of said trays.

It will thus be seen that my invention not 70 only presents a cosmetic container of greater attractiveness than those usually employed, but it also presents means whereby the cosmetic-carrying trays may be so fastened within the device as to make them accidentally practical and to allow of the ready removal from, and placement into, the casing of cosmetic carriers.

I do not limit myself to the particular, size, shape, number or arrangement of parts as 80 shown and described as these are given simply as a means for clearly describing my invention.

What I claim is:—

1. In a container, in combination, a bottom 85 member having a bottom and upwardly extended sides, a frame having an opening therein adapted to be positioned across said bottom member, tray-carrying means carried by one side of said frame preventing the horizontal removal of a tray carried thereby, a removable tray carried by said tray-carrying means and positioned in alignment with said frame opening and means for removably retaining said frame across said bottom member.

2. In a container, in combination, a bottom member having a bottom and upwardly extended sides, a frame having an opening 100 therein adapted to be positioned across said bottom member, tray-carrying means carried by one side of said frame preventing the horizontal removal of a tray carried thereby, a removable tray carried by said tray-carrying means and positioned in alignment with said frame opening, means preventing the removal of said tray when said frame is positioned across said bottom member, and means for removably retaining said frame across 105 said bottom member.

3. In a container, in combination, a bottom member having a bottom and upwardly extended sides, a frame having an opening therein adapted to be positioned across said bottom member, tray-carrying means carried by one side of said frame at opposite sides of said frame opening preventing the horizontal removal of a tray carried thereby, a removable tray carried by said tray-carrying means and positioned in alignment with said frame opening and means for removably retaining said frame across said bottom member.

4. In a container, in combination, a bottom member having a bottom and upwardly extended sides, a frame having an opening therein adapted to be positioned across said bottom member, tray-carrying means carried by one side of said frame at opposite sides of said frame opening preventing the horizontal 125

removal of a tray carried thereby, a removable tray carried by said tray-carrying means and positioned in alignment with said frame opening, means preventing the removal of said tray when said frame is positioned across said bottom member, and means for removably retaining said frame across said bottom member.

5. In a container, in combination, a bottom member having a bottom and upwardly extended sides, a frame having an opening therein adapted to be positioned across said bottom member, inwardly inclined flanges carried by one side of said frame at opposite sides of said frame opening, a removable tray horizontally slidably carried by said flanges and positioned in alignment with said frame opening and means for removably retaining said frame across said bottom member.

20 6. In a container, in combination, a bottom member having a bottom and upwardly extended sides, a frame having an opening therein adapted to be positioned across said bottom member, inwardly inclined flanges carried by 25 one side of said frame at opposite sides of said frame opening, a removable tray horizontally slidably carried by said flanges and positioned in alignment with said frame opening, means preventing the removal of 30 said tray when said frame is positioned across said bottom member, and means for removably retaining said frame across said bottom member.

35 7. In a container, in combination, a bottom member having a bottom and upwardly extended sides, a frame hingedly attached to said bottom member and having an opening therein adapted to be positioned across said bottom member, flanges carried by one side 40 of said frame preventing the horizontal removal of a tray carried thereby, a removable tray carried by said flanges and positioned in alignment with said frame opening and means for removably retaining said frame 45 across said bottom member.

8. In a container, in combination, a bottom member having a bottom and upwardly extended sides, a frame hingedly attached to said bottom member and having an opening 50 therein adapted to be positioned across said bottom member, tray-carrying means carried by one side of said frame, a removable tray carried by said tray-carrying means and positioned in alignment with said frame opening, means preventing the removal of said tray 55 when said frame is positioned across said bottom member and means for removably retaining said frame across said bottom member.

60 9. In a container, in combination, a bottom member having a bottom and upwardly extended sides, a frame hingedly attached to said bottom member and having an opening therein adapted to be positioned across said 65 bottom member, flanges carried by one side of

70
said frame at opposite sides of said frame opening preventing the horizontal removal of a tray carried thereby, a removable tray carried by said flanges and positioned in alignment with said frame opening and means for removably retaining said frame across said bottom member.

10. In a container, in combination, a bottom member having a bottom and upwardly extended sides, a frame hingedly attached to said bottom member and having an opening therein adapted to be positioned across said bottom member, flanges carried by one side of said frame at opposite sides of said frame opening preventing the horizontal removal of a tray carried thereby, a removable tray carried by said flanges and positioned in alignment with said frame opening, means preventing the removal of said tray when said frame is positioned across said bottom member, and means for removably retaining said frame across said bottom member.

11. In a container, in combination, a bottom member having a bottom and upwardly extended sides, a frame hingedly attached to said bottom member and having an opening therein adapted to be positioned across said bottom member, inwardly inclined flanges carried by one side of said frame at opposite sides of said frame opening, a removable tray horizontally slidably carried by said flanges and positioned in alignment with said frame opening and means for removably retaining said frame across said bottom member. 90 95

12. In a container, in combination, a bottom member having a bottom and upwardly extended sides, a frame hingedly attached to said bottom member and having an opening therein adapted to be positioned across said bottom member, inwardly inclined flanges carried by one side of said frame at opposite sides of said frame opening, a removable tray horizontally slidably carried by said flanges and positioned in alignment with said frame opening, means preventing the removal of said tray when said frame is positioned across said bottom member, and means for removably retaining said frame across said bottom member. 100
105
110

13. In a container, in combination, a bottom member having a bottom and upwardly extended sides, a frame having an opening therein adapted to be positioned across said bottom member, flanges carried by one side of said frame preventing the horizontal removal of a tray carried thereby, a removable tray carried by said flanges and positioned in alignment with said frame opening, means for removably retaining said frame across said bottom member and a cover for said device. 115
120
125

14. In a container, in combination, a bottom member having a bottom and upwardly extended sides, a frame having an opening therein adapted to be positioned across said

- bottom member, tray-carrying means carried by one side of said frame at opposite sides of said frame opening preventing the horizontal removal of a tray carried thereby,
- 5 a removable tray carried by said tray-carrying means and positioned in alignment with said frame opening, means for removably retaining said frame across said bottom member and a cover for said device.
- 10 15. In a container, in combination, a bottom member having a bottom and upwardly extended sides, a frame hingedly attached to said bottom member and having an opening therein adapted to be positioned across said
- 15 bottom member, inwardly inclined flanges carried by one side of said frame at opposite sides of said frame opening preventing the horizontal removal of a tray carried thereby, a removal tray slidably carried by said flanges
- 20 and positioned in alignment with said frame opening means preventing the removal of said tray when said frame is positioned across said bottom member, means for removably retaining said frame across said bottom
- 25 member and a cover for said device.

Signed at Attleboro, in the county of Bristol and State of Massachusetts, this 28th day of March, 1932.

ANDREW GRAHAM SHIELDS.
